FRUIT PACKING TRAY

Hugh R. Weiss, Montclair, N.J., assignor to The Pantasote Company, Passaic, N.J., a corporation of New Jersey

Filed Dec. 5, 1961, Ser. No. 67,809

Term of patent 14 years

(Cl. D58—13)

Fig. 4

Fig. 2

Fig. 3

Fig. 4

Fig. 5

FIGURE 1 is a top plan view of a fruit packing tray embodying my new design, a portion being shown diagrammatically in dot-dash lines to indicate repetition of the design;

FIGURE 2 is a side elevational view of the tray of FIGURE 1;

FIGURE 3 is a fragmentary vertical sectional view taken on the line 3—3 of FIGURE 1;

FIGURE 4 is a fragmentary vertical sectional view taken on line 4—4 of FIGURE 1;

FIGURE 5 is a fragmentary vertical sectional view taken on the line 5—5 of FIGURE 1; and

FIGURE 6 is a fragmentary perspective view of the tray of FIGURES 1 to 5.

I claim:

The ornamental design for a fruit packing tray, as shown and described.
